UNITED STATES PATENT OFFICE.

JOHN E. BICKFORD, OF WHITMAN, MASSACHUSETTS.

SHANK-STIFFENER.

No. 834,506.

Specification of Letters Patent.

Patented Oct. 30, 1906.

Application filed March 20, 1906. Serial No. 307,088.

To all whom it may concern:

Be it known that I, JOHN E. BICKFORD, a citizen of the United States, residing at Whitman, in the county of Plymouth and State of Massachusetts, have invented a new and useful Improvement in Shank-Stiffeners, of which the following, taken in connection with the accompanying drawings, is a specification.

My invention relates to a device for rendering the shanks of boots and shoes firm and unyielding to the pressure of the arched part of the foot—that is, the part that should be supported by the "shanking," and it consists in combining with the outer sole a compound shank-piece one part of which is of metal, having its ends bent at about right angles, so as to pass through the other part of the shank-piece to penetrate the outer sole sufficiently to make a firm holding, and thus add to the efficiency of the compound shank-piece, the object being to improve the useful effect of the shank-piece. This object I attain by the means illustrated in the accompanying drawings, in which—

Figure 1 is a vertical section taken through that part of the shoe to which my device relates. Fig. 2 is a plan view of the inside of an outer sole, showing a shank-piece attached.

In the drawings, A represents the outer sole of a boot or shoe, and S a filling part of

the compound shank. This part may be made of leather, leather-board, wood, or any suitable material that will give the required bulk and is durable and would be shaped and molded as required for the style of boot or shoe to which the article is to be applied. The part B should be of plate metal, hard, stiff, and elastic—like tempered steel, for instance. The ends b and b' of this metal plate B are bent down at right angles, as shown in Fig. 1, so as to penetrate the part S and, passing entirely through it, enter the outer sole A, but not pass entirely through it. By this construction I am enabled to utilize the outer sole itself as a part of the shank-stiffener.

I claim—

A shank-stiffening device comprising a filling part shaped and molded for the purpose, and an elastic metal part having its ends bent and driven through the said filling part and adapted to penetrate the outer sole as shown and described.

In testimony whereof I have signed my name to this specification, in the presence of two subscribing witnesses, on this 17th day of March, A. D. 1906.

JOHN E. BICKFORD.
